HENRY B. COATS, OF VEEDERSBURG, INDIANA

VACUUM TANK

Application filed April 20, 1928. Serial No. 271,431.

This application relates to a vacuum tank for use in connection with internal combustion engnies, particularly wherein the fuel reservoir is located at a position below the 5 normal level of the carburetor.

The principal object of the invention is to provide a control mechanism for a vacuum tank of this character, which eliminates the use of a float for controlling the air and liquid lines, as has heretofore been the practice.

One feature of the invention resides in the provision of a valve construction which controls the suction line for drawing the liquid or gasoline into the vacuum chamber and the 15 outlet therefor into the supply tank. This is accomplished by the provision of a dual valve control having one valve member of greater seating area than the other valve member so that the force applied by the vacuum on one valve member will offset to a certain degree the force applied on the other, said valve members controlling the column of liquid drawn into the vacuum tank by 20 making and breaking the partial vacuum created therein, upon the column of liquid reaching different heights. Thus, when the column is of sufficient height to break the vacuum, the valves will be operated to permit it to discharge into the supply chamber and 25 when the column falls to a point wherein the valve is permitted to close a vacuum will again be created and draw more liquid into the vacuum chamber.

Another feature of the invention resides 30 in the valve control return line from the supply chamber which avoids the necessity of providing a separate overflow line to the tank and permits the overflow to pass back to the tank through the feed line leading from the 35 tank to the vacuum chamber. This is accomplished by provided a similar arrangement of valve construction, as will be hereinafter more specifically set forth and described.

The full nature of the invention will be 40 more clearly understood from the accompanying drawings and the following description and claims.

Fig. 1 is a central vertical section through the vacuum tank showing the connections 45 therewith partly in section and partly in ele-

vation. Fig. 2 is the same as Fig. 1 showing a modified form.

In the drawings there is shown a vacuum tank 10 comprising a supply chamber 11 communicating with the carburetor through a tube 12 connected with the lower end thereof. Removably supported upon the vacuum tank there is an upwardly extending cylinder 13 which provides a vacuum chamber 14. The upper end of the vacuum chamber is connected with the intake manifold of an internal combustion engine through a tube 15, provided with an end fitting 16 having a ball valve 17 therein. The ball valve is mounted in a chamber 18 formed in a fitting 16 and is held in position by a perforated plate 19 so as to be capable of closing the relatively larger suction port 20 at the side of which is provided a relatively small suction port 21. Also connected with the fitting 16 there is a gasoline feed line 22 connected at its other end with the main gasoline tank or reservoir 23.

Removably secured within the tank 10 to a removable cover 24 there is a valve mounting 25 provided with a pair of valve seats 26 and 27, in which the valves 28 and 29 are adapted to seat, said valves being connected by a valve stem 30. The valve seat 26 is in communication with the vacuum chamber 14 through a conduit 31 and the valve seat 27 is in communication with said vacuum chamber through a conduit 32 connected with an upwardly extending tube 33 provided with an overturned end 34 near the top of said vacuum chamber. Each of the valve seats 26 and 27 are also in communication with the supply chamber 11. The valve seat 26 and valve 28 are of greater seating area than valve seat 27 and valve 29 for the purpose 30 which will be hereinafter set forth.

The supply chamber 11 is provided with an upwardly extending overflow pipe 35 connected with a tube 36 leading to a valve chamber 37 in the valve housing 38. Said chamber 37 communicates through a connection 39 with the gasoline supply tube 22. Said valve housing is provided with the valve seats 40 and 41, in which the valves 42 and 43, respectively, are adapted to seat. The valve 40

is connected with the overflow tube 36 and the valve 41 is connected through a tube 44 with the air intake 45 mounted in the cover 24 of the tank 10.

In operation, the suction from the motor 5 will create a partial vacuum in the vacuum chamber 14 by reason of the valves 28 and 29 being closed. The vacuum created therein will draw the gasoline from the tank 23 through the tube 22 into said chamber. 10 When the suction is relatively small, air will be drawn from the vacuum chamber into the large port 20 as well as the smaller port 21. In event the suction is increased to a large 15 degree by the operation of the motor, the ball valve 13 will be sucked into closing position against the port 20 so as to shut off said port and thereby cause the suction to be reduced by requiring the air to pass through the 20 smaller port 21.

Upon a sufficient amount of gasoline being drawn into the vacuum chamber 14, the weight of the column of liquid therein will bear directly against the valve 28, tending 25 to open the same while no liquid will bear against the upper valve 29. Thus, there is a balancing of the weight of the column of liquid against the pressure of the air on the valve caused by the partial vacuum. As the 30 air pressure against the valve 28 tending to close the same is slightly greater than the air pressure against the valve 29 tending to open the same, said pressures will be nearly balanced, but since the valve 28 has a greater 35 seating area than the valve 27, the difference in pressure between the two will normally maintain said valves in closed position. Upon this differential air pressure, which is 40 relatively small, being overcome by the weight of the column of liquid, the valves will be forced open and the liquid will freely 45 pass through the valve 28 into the supply chamber 11 until the column in the vacuum chamber and conduit 31 has fallen to a point 50 where the weight of the reduced column fails to overcome the weight of the valves 28 and 29 and their connecting valve stem 30, whereupon the valves will close and again cause the liquid to be drawn into the vacuum chamber to such a height as will cause the cycle, 55 above described, to be repeated.

It will be noted that during the above 60 action the opening of the valve 28 causes the opening of the valve 29 which permits air from the supply chamber 11 to pass upwardly 65 through the tube 33 into the vacuum chamber so as to permit the free flow of liquid therefrom. The weight of the liquid, after the 70 vacuum is broken, will maintain the valves in open position until they are again closed by the action of the vacuum pressure building up more rapidly than the air is allowed to 75 pass through the valves causing the valves 80 to snap shut by reason of the weight of the

valve assisted by the action of the vacuum overbalancing the weight of the liquid.

A distinct advantage is obtained over the float control types of vacuum tanks which cause a slower filling action when the motor 70 is under heavy duty. Inasmuch as the motor under heavy load requires a greater quantity of liquid fuel, this often results in the supply tank being drained before the control valves are operated and a new supply is introduced, as is well known and understood 75 in the art. By reason of this construction there is a more rapid action of the valves since the heavy pull on the motor will create a smaller degree of vacuum requiring a lesser 80 quantity or column of liquid to overcome the action of the vacuum on the valves so as to cause a discharge action through the valves to occur at lesser intervals. Therefore, instead of the supply tank being drained on a 85 long and hard pull, such as climbing a long hill, it will be replenished at closer intervals.

With respect to the overflow, upon the level 90 in the supply tank reaching the top of the overflow pipe 35, the liquid will pass through the tube 36 and have sufficient weight to overcome the differential in pressure exerted on the combined valves 42 and 43, thus opening 95 said valves so as to pass into the chamber 37 and then into the supply tube 22 back to the tank 23. In this connection it will be noted that the valve 43 is of greater seating area than the valve 42 and the atmospheric pressure is exerted on the larger valve 43 through the tube 44 so as to constantly effect a downward 100 pressure on said valves for normally holding them in closed position which pressure is augmented by the suction through the tube 22 by the partial vacuum in the chamber 14 which causes a partial vacuum to be 105 maintained in the chamber 37. When the column of liquid discharging through the overflow pipe 35 is sufficient to overcome this pressure which is in fact the weight of the 110 valves aided by the suction created through the tube 22, said valves will be opened. When 115 said valves are open, air may be drawn into the chamber 14 through the tube 22 from the chamber 37 and tube 44 so that no fluid will be drawn into the vacuum chamber 14 so long as the level in the supply chamber is 120 above the top of the overflow pipe. This prevents the possibility of flooding the motor.

Since the partial vacuum in the tank 14 is 125 broken by the opening of the valves 42 and 43 the liquid passing therethrough will readily return by gravity to the tank 23. However, immediately upon the weight of the column 130 of liquid being reduced so as to permit said valves to close, thereupon the partial vacuum in the tank 14 will immediately draw the liquid not only from the chamber 37 but from the tank 23. Since the seating area of the valve 43 is greater than the seating area of the valve 42 thereby causing the air pressure 135

or partial vacuum represented by the differential size of the valves to be overcome in addition to the weight of the valves, the vibration or movement of the vehicle upon which the tank is used will not act to accidentally open the valves and thereby break the vacuum line to the chamber 14.

In the modified form shown in Fig. 2, there is provided a tank 110 having a supply chamber 111 with an outlet 112 leading to the carburetor. The tank is divided so as to provide a vacuum chamber 113 having a liquid container 114 mounted therein provided with vents 115 near the top thereof. The chamber 113 is connected with the intake of the motor through the tube 116 and the chamber 114 is connected with the supply tank through the tube 117.

There is a vent 118 in the top of the tank 20 communicating with the chamber 113 through the valve 119 which is connected through the valve stem 120 with the flap valve 121 controlling a passage between the chambers 114 and 113 at the bottom thereof.

Chambers 111 and 113 are separated by a partition 122 but are in communication through a valve 123. An overflow standpipe 124 is mounted in the chamber 113 and connected with the overflow tube 125 leading back to the tank. The tank 111 is also provided with an air vent tube 126.

In operation, a partial vacuum is created in the chamber 113 and is also exerted in the chamber 114 through the vents 115 thus drawing liquid through the tube 117 into the chamber 114. Upon the column of liquid in the chamber 114 bearing upon the valve 121 sufficient to overcome the atmospheric pressure exerted on the smaller valve 119, the fluid will flow from the chamber 114 into the chamber 113 and through the valve 123 into the chamber 111.

The invention claimed is:

1. A vacuum tank for elevating liquids comprising a vacuum chamber and a supply chamber, means for creating a partial vacuum in said vacuum chamber for drawing a liquid therein, and a valve positioned intermediate said chambers adapted to be normally held in closed position by the partial vacuum for maintaining the liquid in the vacuum chamber and be opened by the pressure exerted on said valve by reason of the weight of the column of liquid in said vacuum chamber when said pressure is sufficient to overcome the vacuum for permitting said liquid to pass into said supply chamber.

2. A vacuum tank for elevating liquids comprising a vacuum chamber and a supply chamber, means for creating a partial vacuum in said vacuum chamber for drawing a liquid therein, and a pair of valves for controlling the connection between said chambers, one of said valves having a greater seat-65 ing area than the other, means for connecting

said valves so as to cause them to open and close together, the larger of said valves controlling the liquid passage between said chambers and the smaller valve controlling the air passage therebetween.

3. A vacuum tank for elevating liquids comprising a vacuum chamber and a supply chamber, means for creating a partial vacuum in said vacuum chamber for drawing a liquid therein, an air passage between said chambers, a liquid passage therebetween, valves for controlling said passages connected together as a unit and having varying valve seats, the pressure exerted by the partial vacuum tending to close the larger valve and open the smaller one for obtaining a differential of pressure normally holding said valves in closed position and permitting them to be opened for breaking the vacuum upon the weight of the liquid overcoming said differential of pressure.

4. A vacuum tank for elevating liquids comprising a vacuum chamber and a supply chamber, means for creating a partial vacuum in said vacuum chamber for drawing a liquid therein, a pair of connected valves interposed between said chambers, one of said valves being larger than the other, the pressure exerted on said valves by the vacuum tending to close the larger valve and open the smaller valve, whereby the differential in pressure thereon will maintain said valves normally in closed position, one of said valves controlling an air passage and the other controlling a liquid passage between said chambers whereby said valves will be opened when the liquid in said passage is sufficient to exert a pressure adapted to overcome the differential in vacuum pressure exerted thereon.

5. A vacuum tank for elevating liquids comprising a vacuum chamber and a supply chamber, means for creating a partial vacuum in said vacuum chamber for drawing a liquid therein, a valve head secured within one of said chambers having a liquid passage and an air passage communicating therebetween, a stand pipe extending upwardly toward the top of said vacuum chamber and connected with the air passage for preventing liquid from passing therein, a valve for controlling said air passage, a larger valve for controlling said liquid passage and connected with the smaller valve to act as a unit, the pressure created by the vacuum tending to open the smaller valve and close the larger valve, whereby they will be held in normally closed position under a differential of pressure and be opened by the weight of the liquid built up in said passage and vacuum chamber when said differential of pressure is overcome so as to permit the liquid to pass into said supply chamber and cause the vacuum to be broken.

6. The combination with a vacuum tank having vacuum and supply chambers and a

liquid reservoir, of a feed connection between said reservoir and vacuum chamber through which liquid may be drawn therein, of an overflow pipe in said supply chamber, and a valve controlled chamber connected to said feed connection and overflow pipe for permitting excess liquid to pass from said supply tank to said reservoir.

7. The combination with a vacuum tank having vacuum and supply chambers and a liquid reservoir, of a feed connection between said reservoir and vacuum chamber through which liquid may be drawn therein, of an overflow pipe in said supply chamber, a conduit connecting said overflow pipe and feed connection through which excess liquid in said supply tank may pass to said reservoir, and a valve in said conduit adapted to prevent passage of liquid therethrough and seal said feed connection against air intake when in one position, and permit the flow of liquid therethrough while breaking the vacuum and permitting the in-flow of air when in the other position.

8. The combination with a vacuum tank having vacuum and supply chambers, and a liquid reservoir, of a feed connection between said reservoir and vacuum chamber through which liquid may be drawn therein, of an overflow pipe in said supply chamber, a conduit connecting said overflow pipe and feed connection through which excess liquid in said supply tank may pass to said reservoir, and a valve in said conduit adapted to prevent passage of liquid therethrough and seal said feed connection against air intake when in one position, and permit the flow of liquid therethrough while breaking the vacuum and permitting the in-flow of air when in the other position, said valve being actuated by the weight of the column of liquid in said standpipe and conduit.

9. The combination with a vacuum tank having vacuum and supply chambers and a liquid reservoir, of a feed connection between said reservoir and vacuum chamber through which liquid may be drawn therein, of an overflow pipe in said supply chamber, a valve controlled chamber connected with said standpipe and feed connection, a valve in said chamber for controlling the passage of liquid therein from said standpipe, a second valve connected with the first for controlling the passage of air into said chamber, said valves being so arranged that the air pressure on the last-mentioned valve is adapted to maintain said valves normally in closed position while permitting the same to be opened upon the weight of the liquid exerting a pressure against the first-mentioned valve sufficiently to overcome the air pressure on the last-mentioned valve, whereby liquid will be permitted to pass into said chamber through the first-mentioned valve and air

may pass therein for breaking the vacuum through the last-mentioned valve.

10. The combination with a vacuum tank having vacuum and supply chambers, and a liquid reservoir, of a feed connection between said reservoir and vacuum chamber through which liquid may be drawn therein, of an overflow pipe in said supply chamber, and a valve for controlling the passage of liquid from said overflow pipe to said feed connection adapted to normally maintain a vacuum in said feed connection and close the same to said overflow pipe and break the vacuum to said feed connection and open its communication with said overflow pipe when sufficient pressure is exerted thereagainst by a column of liquid in said overflow pipe.

11. In combination, a vacuum tank having vacuum and supplying chambers, a liquid reservoir, a feed connection between said reservoir and said vacuum chamber, an overflow pipe in said supply chamber and a valve so positioned with respect to said overflow pipe as to be operable by the pressure of liquid therein to control the flow of liquid through said feed pipe.

12. In combination, a vacuum tank having vacuum and supply chambers, a liquid reservoir, a feed pipe connecting said reservoir and said vacuum chamber, an air intake open to the atmosphere communicating with said feed pipe, an overflow pipe in said supply chamber and a valve positioned between said air intake and said feed pipe operable by the pressure of liquid in said overflow pipe to control the admission of air into said feed pipe.

13. In combination, a vacuum tank having vacuum and supply chambers, a liquid reservoir, a valve, a conduit connecting said valve and said vacuum chamber, a second conduit connecting said valve and said liquid reservoir, and an overflow pipe in said supply chamber, connecting to said valve, said valve being operable by the pressure of liquid in said overflow pipe to allow the flow of liquid from said supply chamber through said overflow pipe and the second conduit to the liquid reservoir.

14. The combination as defined in claim 13 characterized by the valve simultaneously allowing the flow of liquid as aforesaid and preventing the flow of liquid through the first conduit.

15. In combination, a vacuum tank having vacuum and supply chambers, a liquid reservoir, a feed connection between said reservoir and said vacuum chamber, and a valve operable by the overflow of liquid from said supply chamber to prevent a flow of liquid through said feed connection, said valve having two ports of unequal size.

In witness whereof, I have hereunto affixed my signature.

HENRY B. COATS. 130
